United States Patent Office

Des. 183,359

Patented Aug. 12, 1958

183,359

BATTERY BOX COVER

George R. Mallory, El Cerrito, Calif., assignor to Kimball Manufacturing Corporation, San Rafael, Calif., a corporation of Delaware

Application July 26, 1957, Serial No. 47,101

Term of patent 14 years

(Cl. D26—6)

Fig. 1.

Fig. 2.

Fig. 3.

Fig. 4.

Figure 1 is a perspective view of a battery box cover, showing my new design; Figure 2 is a top plan view; Figure 3 is a front elevational view, the rear being a mirror image thereof, and Figure 4 is an end elevational view, the opposite end being a mirror image thereof. The broken line showing of a battery box in Figure 1 is for illustrative purposes only.

I claim:

The ornamental design for a battery box cover, as shown and described.
